No. 11,322

August 5, 1879

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONN.

DESIGN FOR HANDLES FOR FIRE-IRONS.

Specification forming part of Design No. **11,322**, dated August 5, 1879; application filed May 10, 1879.
[Term of patent 14 years.]

To all whom it may concern:

Be it known that I, RODOLPHE CHRISTESEN, of the city and county of Hartford and State of Connecticut, have invented a new and useful Design for the Handles of Fire-Irons; and I do hereby declare that the following specification, taken in connection with the accompanying photographic illustration forming a part of the same, is a full, clear, and exact description thereof.

The novel design, hereinafter described, is adapted to the handles of fire-irons, and the effect intended to be produced is that of an inverted Japanese vase.

As shown in the accompanying illustration, the portion A is cylindrical in shape, and has its lower end, a, contracted and molded. A series of rings, B, arranged at equal distances apart, surround the lower portion of the cylinder, and from these rings springs a shrub, C, which bears leaves and flowers. A short

ornamental band, D, is arranged diagonally upon the surface, so as to intersect centrally the stalk of the shrub.

The details of the ornamentation may be changed so long as it is confined to the Japanese style, the characteristic feature of the design being the representation of an ornamented inverted Japanese vase, substantially cylindrical as a handle for fire-irons.

What I claim, and desire to secure by Letters Patent, is—

The design for a handle for fire-irons, consisting of the outline corresponding to that of a Japanese vase, substantially cylindrical, and surface ornamentation in Japanese style, substantially as described.

RODOLPHE CHRISTESEN.
